(57) **CLAIM**

I claim the ornamental design for a pull box, as shown and described.

DESCRIPTION

FIG. 1 is a top, front, left side perspective view of a pull box showing my new design;

FIG. 2 is a bottom, rear, left side perspective view thereof; FIG. 3 is a top plan view thereof;

FIG. 4 is a bottom plan view thereof;

FIG. 5 is a front elevation view thereof, the rear elevation view being a mirror image of the front elevation view;

FIG. 6 is a left side elevation view thereof, the right side elevation view being a mirror image of the left side elevation view;

FIG. 7 is a sectional view taken along line 7-7 of FIG. 3;

FIG. 8 is a sectional view taken along line 8-8 of FIG. 3; and, FIG. 9 is an enlarged sectional view of a portion of the pull box taken along line 9 of FIG. 8.

In the Figures, the broken lines illustrate portions of the pull box that form no part of the claimed design.
